UNITED STATES PATENT OFFICE

ROYDEN A. BLUNT, OF BALTIMORE, MARYLAND

DESIGN FOR A BOTTLE

Application filed December 28, 1928. Serial No. 29,432. Term of patent 14 years.

To all whom it may concern:

Be it known that I, ROYDEN A. BLUNT, a citizen of the United States, residing at Baltimore, in the State of Maryland, have invented a new, original, and ornamental Design for a Bottle, of which the following is a specification, reference being had to the accompanying drawing, forming part thereof, in which—

Fig. 2 is a side elevational view of the same, as viewed from the right of Fig. 3, and
Fig. 3 is a rear elevational view of the same.

I claim:
The ornamental design for a bottle as shown.

ROYDEN A. BLUNT.
